UNITED STATES PATENT OFFICE.

ROBERT T. JOHNSTON, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

MACHINE FOR RESURFACING BOWLING-ALLEY BEDS.

1,129,401.

Specification of Letters Patent.

Patented Feb. 23, 1915.

Application filed August 6, 1914. Serial No. 855,367.

To all whom it may concern:

Be it known that I, ROBERT T. JOHNSTON, a citizen of the United States, residing at Chicago, in the county of Cook and State of Illinois, have invented certain new and useful Improvements in Machines for Resurfacing Bowling-Alley Beds, of which the following is a specification.

This invention has relation to bowling alleys and more particularly to means for maintaining the alley bed in perfect condition.

Bowling alley beds should be kept perfectly horizontal and level to obtain the best results but constant rolling of the ball down the center or diagonally across the bed rolls or wears a groove or grooves in the surface of the bed, and sometimes the surface becomes irregular or wavy because of swelling or shrinkage of the wood or settling of the walls or foundation. It is necessary at times to remove the gutters to level up the bed from underneath, but the usual practice is to cut down the high spots with hand planes and smooth the surface with sandpaper.

This is slow and tedious and expensive work, and uncertain at best because of the difficulty of leveling a large area by hand with the tools available.

30 In my companion application Serial No. 855,365, filed August 6, 1914, I have disclosed a method of leveling bowling alley beds which contemplates first obtaining a guide level by a such a machine as is disclosed in my application Serial No. 855,366, filed August 6, 1914, and then cutting down the surface to such predetermined level by the machine which forms the subject of this application.

40 The object of this invention is to provide a machine which will operate to cut down the surface of a bowling alley bed to a predetermined level.

A further object is to provide for automatically reversing the machine to cut back and forth across the bed so that the sandpaper employed for the cutting operation may be used repeatedly in both directions. And a further object is to provide for cutting the surface of the bed upward at its edge instead of flatwise down upon the surface so that the sandpaper will not fill up with dust of the surfacing material.

The invention has other objects in view

which will appear more fully hereafter in

the detail description thereof as embodied in the machine illustrated in the accompanying drawings in which—

Figure 1 is a plan view of the machine on a portion of a bowling alley; Fig. 2 is a front elevation of the machine with the bed in section; Fig. 3 is an end view of the machine showing the bed in section; Fig. 4 is a detail sectional view showing the reversing mechanism; Fig. 5 is a longitudinal sectional view of the machine; Fig. 6 is a detail sectional view showing a guide and supporting shoe.

Referring to the drawings, 7 is the frame of the machine which is supported on adjustable elements 8 arranged to travel on the alley bed 9, preferably in level guide grooves 10 therein according to the inventions of my companion applications aforesaid.

A roll of sandpaper 11 is mounted in 75 brackets 12 on the frame and rests upon rolls 13, 14 suitably journaled in the frame. Another roll 15 is mounted in brackets 16 on the machine to take up the sandpaper from roll 11 and this roll 15 also rests upon rolls 17, 18. The sandpaper is caused to travel back and forth from one roll to the other, the supply and take-up rolls being revolved by the rolls 13, 14, 17, 18, and the sandpaper running from one to the other roll 11, 15 over rolls 13, 17, which thus form end guides for the sandpaper. The rolls 13, 17 are driven by sprocket chains 19, 20 operating on sprockets 19', 20' on the main shaft 21 which is driven from the motor 22 by sprocket chain 23. Rolls 14, 18 are driven by sprocket chains 24 from the rolls 13, 17 by suitable chains and sprockets. Thus the rolls 11, 15 are caused to revolve in the same direction

80 over rolls 13, 17, which thus form end guides for the sandpaper. The rolls 13, 17 are driven by sprocket chains 19, 20 operating on sprockets 19', 20' on the main shaft 21 which is driven from the motor 22 by sprocket chain 23. Rolls 14, 18 are driven by sprocket chains 24 from the rolls 13, 17 by suitable chains and sprockets. Thus the rolls 11, 15 are caused to revolve in the same direction to feed off the sandpaper from one and take 85 it up on the other by the carrying and driving rolls 13, 14, 17, 18, on which the sandpaper rolls are caused to revolve. The sandpaper extends across the machine beneath the frame and a pressure roller 25 is arranged to travel back and forth across the bed and press the sandpaper to its work on the surface of the bed. This roller is mounted in shoes 26 (Fig. 3) which travel on guides 27 on the frame and are fastened to sprocket chains 28 mounted to travel on sprockets 29 at each end of the frame.

100 The shaft 30 of roll 17 has worm and gear connections 31 with the shafts 32 of sprockets 29 to drive the chains 28 but the

pressure roller 25 is caused to travel at lower rate of speed than that of the paper. Preferably the roller will travel across the bed once while the paper is being wound from one roll to the other and then as the operation is automatically reversed the roll travels back again and the paper is rewound on its original roll. Thus the paper travels in the same direction as the roll but at a higher rate of speed.

Any suitable automatic or manual reversing mechanism may be employed. One form is illustrated in Figs. 2 and 4 and comprises a bevel gear 33 on main shaft 21 to mesh 15 with bevel gear 34 on horizontal shaft 35 which carries a worm 36 driving worm gear 37 suitably mounted to drive worm gear 38 on shaft 39 which carries cam 40. A clutch frame 41 carries a clutch member 42 which 20 engages clutch member 43 on the differential casing 44 inclosing differential gear 45 on main shaft 21. The frame 41 is engaged with a groove 45 in the frame of motor 22 and has a fork 46 to engage the grooved 25 collar 47 of a clutch member 48 on shaft 21, this clutch member being arranged to co-act with clutch member 49 on the casing 44. An arm 50 on the frame 44 is pivotally connected with a lever 51 which is pivotally mounted at 52 and has its free end arranged 30 to engage the cam 40.

Referring to Fig. 4, the reversing mechanism is in neutral position. The cam 40 causes the frame 41 to move back and forth 35 throwing first one clutch in and the other out and then the one out and the other in. When the clutch members 42, 43 are engaged the shaft 21 will be driven in one direction since the frame 41 will hold the differential 40 casing rigid, but when clutch members 48, 49 are engaged the casing is released and may turn to rotate the shaft 21 in the opposite direction.

In practice, my machine is arranged on 45 the alley bed with the pressure roller above one gutter 53 to cause the sandpaper to engage the side edge of the alley with an up-percute and this action continues entirely across the bed, transversely of the grain of 50 the wood, and is repeated in reverse direction. The machine is moved lengthwise of the alley as the transverse cutting continues until the entire bed has been covered. I prefer to go over the bed first with coarse 55 sandpaper to give it a rough cut and then with finer sandpaper to give it a smooth cut. It is desirable to undercut the surface because in this way I avoid filling up the sandpaper with the dust of the shellac and finish 60 coatings and wood removed by the sandpaper from the surface of the alley and this I accomplish by setting the shoes 8 accordingly and running the pressure roller beyond the side edges of the bed and above the 65 gutters sufficiently. Then as it travels

across the bed the pressure roller will operate to hold the sandpaper to its work and the latter will throw the dust forward in the direction of its travel, practically cleaning itself as it travels. On each side of the 70 roller the sandpaper extends upward at an angle to the plane of the work. By reversing the travel of the sandpaper it may be used repeatedly before it becomes too dull. In the particular embodiment of the invention 75 illustrated in the drawings the roller 25 is journaled to revolve in its travel but it is not necessary that the roller should revolve and it may be fixed in its bearings to act as a shoe, or any other pressure device suitable 80 for the purpose may be employed, and whenever the word "roller" is used in this connection it will be understood to cover and include any suitable pressure device, such as a revolving roller, a stationary roller, or a 85 shoe.

I claim:

1. In a machine of the class described, the combination of a frame, a pair of rolls mounted on the frame, a supply of sandpaper disposed upon said rolls, means for continuously transferring the paper from one roll to the other, and means for pressing the paper into contact with the work along a line movable with respect thereto. 95

2. In a machine of the class described, the combination of a frame, a pair of rolls mounted on the frame, a supply of sandpaper disposed on said rolls, means for continuously transferring the paper from one 100 roll to the other, and a pressure roller for holding the paper in contact with the work along a line movable with respect thereto.

3. In a machine of the class described, the combination of a frame, a supply roll and 105 a take-up roll mounted on the frame, a supply of sandpaper on the supply roll and running to the take-up roll, means for continuously moving the paper between said rolls and a pressure roller located below 110 the supply and take-up rolls and engaging the sandpaper between said rolls to hold it to its work, the sandpaper on each side of the pressure roller extending upward at an angle to the plane of the work. 115

4. In a machine of the class described, the combination of a frame, a supply roll and a take-up roll mounted on the frame, a supply of sandpaper on the supply roll and running to the take-up roll, a bodily movable 120 pressure roller operating upon the sandpaper between the rolls to hold it to its work, and means for causing the sandpaper and the roller to travel always in the same direction.

5. In a machine of the class described, the combination of a frame, a supply roll and a take-up roll mounted on the frame, a supply of sandpaper on the supply roll and running to the take-up roll, a pressure roller 125 130

- operating upon the sandpaper between the rolls to hold it to its work, and means causing the sandpaper to travel from the supply roll to the take-up roll and the roller to travel with the sandpaper but at a slower rate of speed from one end of the machine to the other.
6. In a machine of the character described, the combination of a frame, a pair 10 of rolls on the frame alternately constituting a supply roll and a take-up roll, a supply of sandpaper running from the supply roll to the take-up roll, a pressure roller operating on the sandpaper between said rolls 15 to hold it to its work, means for causing the sandpaper and roller to travel together but at different rates of speed, and means for automatically reversing the direction of travel of the sandpaper and roller.
7. In a machine of the character described, the combination of a frame, elements adjustably secured on the frame for supporting the same, a pair of rolls on the frame alternately constituting a supply roll 20 and a take-up roll, a supply of sandpaper running from the supply roll to the take-up roll, a pressure roller operating on the sandpaper between and below said rolls to hold it to its work, and means for causing the sandpaper and the roller to travel back and forth together but at different rates of speed.
8. In a machine of the character described, the combination of a frame, a pair of rolls alternately constituting a supply 30 and a take-up roll, a pair of driven rolls supporting and revolving said supply and take-up rolls, a supply of sandpaper on the supply roll running over the outer of each of said pairs of rolls to the take-up roll, and a pressure roller operating on the sandpaper below said pairs of rolls to hold the sandpaper to its work on a line through the center of said roller.
9. In a machine of the character described, the combination of a frame, a pair 40 of rolls alternately constituting a supply and a take-up roll, a supply of sandpaper running from the supply to the take-up roll, a pressure roller operating on the sandpaper to hold it to its work, guides on the frame, 45 shoes supporting the roller and arranged to travel on said guides, and means for causing the roller and sandpaper to travel together but at different rates of speed.
